UNITED STATES PATENT OFFICE.

GILBERT RIMMER, OF LONDON, ENGLAND, ASSIGNOR TO SULLIVAN MACHINERY COMPANY, OF CHICAGO, ILLINOIS, A CORPORATION.

FLITTING-TRUCK OR TROLLEY FOR COAL-CUTTING MACHINES.

Application filed June 16, 1924, Serial No. 720,419, and in Great Britain September 21, 1923.

This invention relates to flitting-trucks or trolleys for coal-cutting machines.

The present invention provides a truck or trolley having a frame or platform constructed to receive and support a coal-cutting machine, combined with an air-driven motor independent of said coal-cutting machine mounted on said trolley and a driving connection between said motor and the trolley-wheels.

In one form of the invention the flitting-truck or trolley comprises two or more pairs of wheels, a frame or platform supported by said wheels and having a portion of the frame, including that part which overlies the wheel-base, arranged to receive and support a coal-cutting machine, an air-driven motor independent of the coal-cutting machine mounted on the frame or platform aforesaid beyond one end of the wheel-base, and a driving connection between said motor and the trolley-wheels.

In one well-known type of cutting machine the cutting operation is effected by an endless chain armed with cutting tools or picks and driven round the margin of a jib, which jib is pivoted at one end of the body of the machine and is capable of being slewed in a horizontal plane. A truck or trolley arranged to support a coal-cutting machine of the above type is, according to this invention, characterized in that the frame or platform of the trolley, at that end remote from the trolley-propelling motor, is so constructed as to permit of the slewing of the jib and of the operation of the cutter-chain while the cutting machine is supported on the trolley.

Preferably, the driving connection between the trolley-propelling motor and the trolley-wheels includes a combined clutch-and-reversing mechanism operable at will to control the transmission of the motor drive. By this mechanism the trolley may be driven in either direction, or the motor drive may be disconnected from the trolley-wheels, whichever condition is required.

A further feature of the present invention comprises the combination of a flitting-trolley as described above, with a winding-drum mounted on the trolley frame and a driving connection between the trolley-propelling motor and said winding-drum.

The purpose of this winding-drum will be hereinafter explained.

55

The foregoing and other features of the invention will be better understood from the following description, given by way of example, of one preferred embodiment.

Reference will be made to the accompanying drawings (largely diagrammatic), in which—

Figures 1, 2 and 3 show the trolley in side elevation, plan and end elevation respectively: In Figure 1 the position of the coal-cutting machine when mounted on the trolley is indicated in chain lines.

Like reference numerals indicate like parts in the three views.

The trolley comprises an open rectangular frame 10 supported upon two pairs of wheels 11, 12 spaced apart one behind the other and running on rails 40. The frame at one end (hereinafter termed the tail-end) extends considerably beyond the wheel-base and is arranged to carry at said end a trolley-propelling motor 13. The side members of the frame are angle iron bars, the horizontal flanges of which constitute ledges to receive and support a coal-cutting machine.

The driving mechanism of the trolley is arranged as follows:—The prime-mover 13 is an air-driven motor constructed and operating substantially in the manner of the hoisting mechanism described in United States Specification No. 430,211, filed Dec. 13, 1920, that is to say, the motor and reduction gearing therefor are enclosed within a drum rotatable by said motor. This unit is as shown mounted at the tail-end of the trolley frame, with the axis of the drum disposed at right-angles to the lengthwise direction of the frame, that is with the drum axis parallel to the axles of the trolley-wheels. The motor-driven drum is carried by underslung brackets 14 tied to the side members of the trolley frame. Rotation of the drum is transmitted to the trolley-wheels through mechanism comprising two shafts 15, 16 parallel to the drum axis and located one at a higher level than the other and both in front of the drum. The shafts are supported at their ends by brackets (not shown) attached to the trolley frame. The upper shaft 15 is

adapted to be continuously driven by a chain 17 from the drum, and the drum and shaft are provided with chain-sprockets 18, 19 for this purpose. Conveniently the drum 5 sprocket 18 is secured to the drum by clamping rings 20. The lower shaft 16 has mounted upon it a spur-wheel 21 and a chain-sprocket 22, spaced apart and both capable of rotating freely upon the shaft. 10 The spur-wheel 21 is in mesh with a similar wheel 23 fast upon the upper shaft 15 and the sprocket 22 is chain-driven from a similar sprocket 24 on the upper shaft. As will be seen the arrangement is such that the 15 spur-wheel 21 and chain-sprocket 22 on the lower shaft are rotated in opposite directions by their respective driving connections with the upper shaft. Mounted in the lower shaft between the aforesaid spur-wheel 21 and sprocket 22 is a clutch-member 25 rotatable with the shaft but capable of axial sliding movement thereon. The 20 clutch-member 25 on movement to one side is adapted to engage the spur-wheel 21 and on movement to the other side to engage the chain-sprocket 22 while in its mid position both spur-wheel and chain-sprocket are "free". The two trolley-wheel axles are interconnected by a driving chain 31, 25 and the rearmost axle is driven by a chain 32 from the lower shaft 16.

The position of the clutch-member is controlled by a lever 26 at the tail-end of the trolley frame. The lever 26 is connected at 30 its lower end to a spindle 27 which is carried by brackets 28 depending from the trolley frame and engaging the ends of the spindle. Support for the spindle is also afforded by the motor-supporting brackets 14 through the lower flanges of which the spindle is threaded. Connected to the spindle 35 27 at that end remote from the control lever 26 are two radial arms 29 provided at their outer ends with studs 30 which project in a direction towards one another and engage in a circumferential groove on the clutch member 25. In the mid position of the lever 26 (shown in Figure 3) the clutch member 25 is also in its mid position and there is therefore no drive to the trolley 40 wheels. Movement of the lever to the right or to the left causes the clutch to engage the spur-wheel 21 or the chain sprocket 22 and the trolley to be propelled in either the forward or reverse direction. The lever 26 may be locked in any one of its three positions say by a pin passed through the lever at 31 and entered in one of three holes in the cross member at the tail of the trolley frame. 45

50 The motor-driven drum 13, in addition to transmitting motion to the trolley-wheels, is adapted, when required, to serve as a winding-drum. Where the road over which the trolley is to be flitted is of steep gradient it 55 may not be possible to obtain sufficient trac-

tive effort from the trolley-wheels. In such cases a haulage-cable (not shown), e. g. a wire rope, may be attached at one end to that portion of the winding-drum which is not occupied by the chain sprocket 18 and at its free end to an anchor positioned at any convenient distance in front of the trolley. On rotation of the winding-drum the trolley 75 would then be caused to haul itself along the rope. 75

The trolley, in the example at present under consideration, is designed to flit a coal-cutting machine of the aforesaid type in which a pivoted jib is carried at one end of the body of the machine. As shown in chain 80 lines in Figure 1 the machine 33 when loaded on the trolley lies lengthwise along the frame of the latter and over the wheel-base, the jib section 34 being outermost, i. e. at that end 85 of the frame remote from the trolley-propelling motor. The trolley will be so designed with regard to the spacing of the trolley-wheels, the extent to which the tail-end of the machine projects beyond the wheel-base and the position of the propelling mechanism on said projection, that the moment applied by said propelling mechanism 90 will be balanced by the weight of the cutting machine acting over the wheel-base. 90

The trolley described above may be employed solely for flitting purposes, or in addition it may be used as a support for the cutting machine while the latter is in operation, that is to say, the machine may be more or less permanently mounted upon the trolley. In the latter case the trolley is necessarily so constructed as to permit of the operation of the cutting machine while the latter is mounted on the trolley frame. To this end the vertical flanges of the side 100 members of the frame, at the front end thereof, are cut away at 35 so as to allow of the swinging movement of the pivoted jib 34 through an angle of approximately 180°, that is from a position on one side of the frame at right-angles to the body of the machine to a similar position on the other side of the frame. The cutting machine may be of the well-known type in which propulsion of the machine, along a face, while the cutting operation is in progress, is effected by a chain along which the machine hauls itself; and in which the slewing of the jib is also effected by the haulage chain. In one such machine there are chain sprockets at 105 the corners of the haulage section around which, or around one of which, the chain in some circumstances is required to pass. One of the corner sprockets is indicated at 36 in Figure 1. When the above machine 110 is supported on the trolley the corner chain sprockets would lie below the top of the side members of the trolley frame, and in order to afford ample clearance for the passage of the chain around these sprockets and to en- 115

sure the proper operation of the latter; driven motor independent of the coal-cutting notched recesses 37 are cut in the vertical machine mounted on the trolley frame beyond the flanges of the side members of the frame at positions adjacent to the corner sprockets.

5 A truck or trolley constructed according to the present invention is primarily intended for use in collieries where the cutting machines are driven by compressed air; the motive fluid for the trolley-propelling motor being obtained from the same source as that serving the cutting machines themselves. In practice the trolley-propelling motor will be of considerably smaller horse power than that of the cutting machine motor; and an air 10 hose of comparatively small diameter—in relation to that of the hose serving the motor of the cutting machine—will be employed to supply the trolley motor. For example a cutting machine provided with a 30-50 h. p. air-motor and requiring a supply hose of at least two inches in diameter can be flitted on a trolley made according to the present invention and provided with an air-motor turbine of 8-10 h. p. served with a hose of 15 $\frac{1}{2}$ inch- $\frac{3}{4}$ inch in diameter. Considering the narrow confines of a colliery it is obviously an advantage to be able to use a small diameter hose for flitting purposes.

It is to be understood that the present invention is not limited to the detailed construction described above. Thus the trolley-propelling motor can be replaced by any other convenient form of air-driven motor, and similarly the clutch-and-reversing mechanism may be modified without departing from the spirit of the invention.

I claim:

1. A flitting trolley for a coal-cutting machine comprising in combination a frame carried upon wheels and constructed to receive and support a coal-cutting machine, an air-driven motor independent of said coal-cutting machine and mounted on the trolley frame, and a driving connection between 40 said motor and the trolley wheels including a power transmitting element surrounding said motor.

2. A flitting trolley for a coal-cutting machine comprising in combination a frame carried upon wheels and constructed to receive and support a coal-cutting machine, an air-driven motor independent of said coal-cutting machine and mounted on the trolley frame, and a driving connection between 50 said motor and the trolley wheels including a power transmitting element surrounding said motor and rotating on an axis parallel to the truck wheel axes.

3. A flitting trolley for a coal-cutting machine comprising in combination a plurality of pairs of wheels, a frame supported by said wheels and having a portion of its upper surface, including that part which overlies the wheel-base, arranged to receive 60 and support a coal-cutting machine, an air-

driven motor independent of the coal-cutting machine mounted on the trolley frame beyond one end of the wheel-base, and a driving connection between said motor and the trolley wheels.

4. A flitting trolley for a coal-cutting machine comprising in combination a frame mounted on wheels and constructed to receive and support the coal-cutting machine and to permit of the operation of the machine, to effect cutting, while so supported, an air-driven motor independent of said cutting machine mounted on the trolley frame, and a driving connection between 70 said motor and the trolley wheels including a power transmitting element surrounding said motor.

5. A flitting trolley for a coal-cutting machine comprising in combination a frame mounted on wheels and constructed to receive and support the coal-cutting machine and to permit of the operation of the machine, to effect cutting, while so supported, an air-driven motor independent of said cutting machine mounted on the trolley frame, and a driving connection between 75 said motor and the trolley wheels including a power transmitting element surrounding 80 said motor.

6. A flitting trolley for a coal-cutting machine of the pivoted-jib type comprising a plurality of pairs of wheels, a frame carried by said wheels, arranged to support the coal-cutting machine over the wheel-base, and so formed at that end which will be adjacent the machine jib as to permit of the slewing of said jib while the machine is on the trolley, an air-driven motor independent of the cutting machine mounted on the trolley frame beyond the wheel-base and at that 85 end of the frame remote from the jib-receiving portion, and a driving connection between the motor and the trolley wheels.

7. A flitting trolley for a coal-cutting machine comprising in combination a frame constructed to receive and support the machine, an air-driven motor independent of the coal-cutting machine mounted on the trolley frame, a driving connection between 90 said motor and the trolley wheels including a power transmitting element surrounding said motor, and a combined clutch-and-reversing mechanism operable at will to control the transmission of the drive through 95 the driving connection aforesaid.

8. A flitting trolley for a coal-cutting machine comprising in combination a frame constructed to receive and support the machine, an air-driven motor independent of the coal-cutting machine mounted on the trolley frame, a driving connection between 100 said motor and the trolley wheels including a power transmitting element surrounding 105 said motor and rotatable on an axis parallel 110 to the truck wheel axes.

to the truck wheel axes, and a combined clutch-and-reversing mechanism operable at will to control the transmission of the drive through the driving connection aforesaid.

5. 9. A flitting trolley for a coal-cutting machine comprising in combination a plurality of pairs of wheels, a frame supported by said wheels and constructed to receive and support the coal-cutting machine, an air-driven motor independent of said cutting machine mounted on the trolley frame, a driving connection between said motor and the trolley wheels, and a winding-drum mounted on the trolley frame and rotated 15 by said trolley propelling motor, said drum and motor being arranged in the same transverse zone on said trolley frame.

10. A flitting trolley for a coal-cutting machine comprising in combination a plurality of pairs of wheels, a frame carried by said wheels and arranged to support the cutting machine, a motor-driven drum mounted on the trolley frame, and a driving connection between the motor-driven drum 25 and the trolley wheels.

11. The combination with a flitting trol-

ley, of a coal cutting machine mounted thereon, an air-driven motor supported on the trolley and independent of the cutting machine, said motor having a power transmitting element rotating on an axis transverse to the truck, and spaced longitudinally of said truck from said coal cutting machine, and a driving connection between the motor and the trolley wheels. 30

12. The combination with a coal-cutting machine of the pivoted-jib type, of a flitting trolley having a frame carried upon wheels and supporting the coal-cutting machine substantially directly over the wheel-base, the portion of the frame adjacent to the machine jib being sufficiently open to permit of the slewing of said jib, an air-driven motor independent of the coal-cutting machine mounted on the trolley frame 40 beyond the wheel-base and at that end of the frame remote from the machine jib, and a driving connection between the motor and the trolley wheels. 45

In testimony whereof I have signed my name to this specification. 50

GILBERT RIMMER.
